UNITED STATES PATENT OFFICE.

CHARLES LAURENCE BURDICK, OF LONDON, ENGLAND.

COLOR-PRINTING MACHINE.

No. 836,483.

Specification of Letters Patent.

Patented Nov. 20, 1906.

Application filed February 23, 1905. Serial No. 246,966.

To all whom it may concern:

Be it known that I, CHARLES LAURENCE BURDICK, a citizen of the United States, residing at London, in the county of Middlesex, England, have invented a certain new and useful Improvement in Color-Printing Machines, (Case No. 5,) of which the following is a full, clear, concise, and exact description, reference being had to the accompanying drawings, forming a part of this specification.

My invention relates to coloring or printing machines, and is particularly adaptable for coloring photographs, post-cards, posters, or the like or for coloring original designs for decorative purposes by means of stencils and may be employed to decorate such articles as tiles, wood blocks, or the like.

Broadly speaking, my invention consists in causing a transfer-frame to be reciprocated transversely across a supporting-frame to carry the objects to be colored successively through coloring fields or below stencils over which sprayers are adapted to travel to convey coloring-matter to the object. Any number of such coloring-fields may be employed and each object being successively carried through the various fields to receive at each time a different color or the same color applied in a different manner or from a different direction.

My invention will be best understood by referring to the accompanying drawings, in which—

Figure 1 is a side elevation of the machine.

Fig. 2 is a plan view thereof. Fig. 3 is a sectional view taken on line 3 3 of Fig. 1; and Fig. 4 is a sectional view taken on line 3 3 of Fig. 1, the card-supporting table being shown in a different position.

Like reference characters refer to like parts throughout the various figures.

A framework 1 is placed at one end of a supporting frame or table 2, and below the frame 1 in said table is provided a transverse channel 3, in which is disposed a table 4. This table has side ridges 5 5 and legs 6 6, extending from the center plate 7. Between the ridges 5 is disposed a reciprocating carrier-frame 8, consisting of side rods 9 9, from which short fingers or extensions 10 10 extend upwardly at intervals. The top surfaces of the rods 9 normally lie in the same plane with the top surfaces of the table-ridges 5, and the fingers 10 extend upwardly a sufficient distance from the rods to engage the edge of the objects to be colored, these

objects normally resting on the top surfaces of the rods 9 and ridges 5. The carrier-frame rests on cross-bars 11 11, secured to the table 2, and a rack-bar 12 extends from one end of the carrier-frame and is provided with side teeth 13 for engagement with a gear-wheel 14, pivoted at the end of a supporting-arm 15, extending from the frame 2. As the gear-wheel 14 is revolved the rack-bar will be engaged to reciprocate the carrier-frame longitudinally within the table-ridges 5 and transversely across the supporting-frame 2.

The supporting-table is divided into a plurality of coloring sections or fields 16 16, of which there may be any number, and a stencil 17 may be provided for each section secured above the object-supporting table and reciprocating carrier-frame, and the object to be colored is pressed against the stencil as the object-supporting table is moved to its uppermost position. To cause this vertical reciprocation of the object-supporting table 4, lugs 18 are secured to the under side of the center plate 7 thereof, each lug 18 having a vertical elongated bearing 19. Shafts 20 pass through these elongated bearings, and extending from said shafts are cam-arms 21 for engaging the under side of the center plate 7, and at one end of said shafts 20 are secured actuating-arms 22, pivoted at their free ends in slots 23, provided in the horizontal actuating-bar 24. The table 4 normally rests at the bottom of the channel 3, and the shafts are disposed at the top of the elongated bearings 19, the cam-arms being horizontal and the actuating-arms 22 being vertically disposed, as shown in Fig. 4 and in dotted lines in Fig. 1. As the actuating-bar 24 is moved toward the left the shafts 20 will be moved to the lower end of the vertical slots 23, and the cam-arms 21 will engage the plate 7 to move the table upwardly to the position as shown in Fig. 3 and in full lines in Fig. 1, and the objects to be colored are pressed into engagement with the stencils.

The frame 1 is provided with horizontal guideways or tracks 25, in which a sprayer-frame 26 is adapted to be reciprocated. One or more sprayers 27 may be provided for each coloring field or section and are suitably secured to the sprayer-frame 26, being fed with coloring material through connections 28, communicating with vessels 29, supported from the upright frame 30. Compressed air is supplied to the sprayers through the con-

nections 31. The flow of coloring-matter and compressed air through the sprayers is controlled by the valves 32 and 33, respectively, the valve-actuating levers 34 being pivoted at 35 and terminating at their free ends in rollers 36. In suitable positions on the frame 1 are secured cam-ridges 37, which as the sprayer-frame is reciprocated across the frame 1 engage the valve-lever rollers 36 to raise the levers and to open the sprayer-valve, whereby coloring-matter is sprayed to the object as the sprayers travel across the stencil.

To prevent the accumulation of coloring-matter on the stencil and also to prevent discoloring of the cards, I provide cleaning mechanism in the shape of suction-brushes, which are carried over the stencils, and these suction-brushes consist of a tubular body part 38, having an outlet-channel 39, which engages the stencils. The tubular part is connected through piping 40 with some suction source, (not shown,) and as the brushes are moved across the stencil the surplus coloring-matter is carried into the channels 39 and conveyed away through the piping 40.

I shall now describe the various means employed for causing the reciprocation and other movements of the various parts.

At the other end of the machine a shaft 41 is journaled in bearing-standards 42 42, secured to the supporting-frame 2 of the machine, and a drive-wheel 43, engaged by a belt 44, is adapted for driving engagement with the shaft 41 upon actuation of the clutch mechanism 45. A crank-arm 46, secured at one end of the shaft, engages one end of the forked frame 47, whose other ends are pivoted to the sprayer-frame 26. At the other end of the shaft is mounted a gear 48, which meshes with another gear 49, pivoted at 50 to the side of the supporting-frame 2. Also pivoted at 50 and fixed with relation to the gear 49 are cams 51 and 52. The cam 51 is in the shape of a circular disk having an eccentric portion 51' extending part way about its circumference. A cam-roller 53, pivoted to the end of the actuating-rod 24, is engaged by the cam 51 to cause periodic horizontal reciprocation of the bar 24 and vertical reciprocation of the object-supporting table, as before described. The cam 52 has an eccentric arm portion 54 and is adapted for engagement with the cam-roller 55, pivoted to the end of the actuating-bar 56, which terminates at its other end in an elongated bearing 57, engaging a crank-pin 58, secured to the gear-wheel 14. Upon rotation of the cam 52 the actuating-bar 56 is horizontally reciprocated, while the carrier-frame is reciprocated transversely across the supporting-table 2 and longitudinally within the object-supporting table. The bars 24 and 56 travel through guideways or guide-frames 59 60, and tension-springs 61 62, respectively,

engage the bars 24 and 56 and suitably connect with the supporting-frame 2 or with the guide-frame 60, as shown.

The operation of the machine is as follows: The rotation of the gear-wheels is in the direction as shown by arrows, and in the position shown the roller 53 is about to engage the eccentric part 51' to release the actuating-bar 24 and to allow the object-supporting table to return to its lower position within the channel 3. The rack-bar 12 is also in its outer position to receive the uncolored object o' . The sprayer-frame is away from the stencils and the sprayer-valves closed. As the roller 53 enters the eccentric portion 51' of the cam 51 the object-table will drop to carry the objects o^2 o^3 from the stencils, and while the roller 53 engages the part 51' the cam-arm 54 will engage the roller 55 to actuate the bearing 56 to cause rotation of the gear 14 and an inward stroke of the rack-bar and carrier-frame, the distance being just sufficient to carry the uncolored object o' into the coloring field or section 15 below the stencil 17, or, in other words, to assume the position just vacated by the object o^2 , which has moved to the adjacent section 16 to occupy the space vacated by the object o^3 , which object o^3 will be supported on the carrier-frame over a receptacle 65, as shown in Fig. 4. As the roller 53 now again engages the concentric part of the cam 51 the bar 24 will be moved to again cause the object-table to be carried upwardly to press the objects thereon into engagement with the stencils. At the same time, however, the cam-arm 54 allows the bar 56 to be returned by the spring 62 to cause reverse rotation of the gear 14 and the withdrawal of the carrier-frame to its initial position to receive another uncolored object. As best seen in Figs. 3 and 4, detents in the shape of pawls 66 are employed, which allow the objects to be carried thereby over the receptacle; but upon return of the carrier-frame these pawls engage the objects and cause their removal from the carrier-frame to be deposited in the receptacle. While the roller 53 travels about the concentric portion of the cam 51 the crank-arm 46 is being actuated to cause the fork-frame 47 to reciprocate the sprayer-frame across the framework 1, and upon engagement of the valve-lever rollers by the cam-ridges 37 the valves will be actuated to allow coloring-matter to be blown through the stencils and on the objects, the coloring-matter being delivered so long as the rollers engage these ridges. As the roller 53 again reaches the end of the concentric portion of the cam 51 the crank-arm 46 is in position, as shown in Fig. 1, to remove the sprayers from the coloring field and to close the valves thereof. The cycle of operations thus described is again repeated and the object-supporting table again lowered to deposit the colored objects

on the carrier-frame, which is thereupon reciprocated to advance the objects from one coloring field to the other and to deposit a finished card or object in the receptacle.

5 By providing a plurality of coloring fields or sections any combination of colors may be distributed over the cards, and the sprayers also may be adjustable, so that the coloring-matter may be applied from various directions or at various angles.

Many changes also may be made in the construction and arrangement of the machine and its various mechanisms without departing from the spirit of invention, and I do not, therefore, wish to be limited to the exact arrangement and construction herein shown.

I claim as new and desire to secure by Letters Patent—

1. In a pattern-printing machine, the combination with a main supporting-frame, of a stencil secured thereto, a supporting-table below said stencil for supporting objects to be printed, means for raising said table to carry the object thereon into engagement with said stencil, coloring means for applying coloring-matter to the object when engaging the stencil, and carrier mechanism for periodically removing the printed object away from the stencil and for conveying an uncolored object to the table in position below the stencil.

2. In a pattern-printing machine, the combination with a main supporting-frame, of a stencil secured thereto, a supporting-table for supporting objects to be colored, carrier mechanism for conveying an uncolored object below said stencil, means for causing said supporting-table to carry the object into engagement with the stencil, sprayers adapted to be moved above the stencil, and means for causing actuation of said sprayers to deposit coloring-matter only when the objects are held in engagement with said stencil by the supporting-table.

45 3. In a pattern-printing machine, the combination with a main supporting-frame divided into a plurality of sections, a stencil for each section, a supporting-table for supporting the objects to be colored, conveying mechanism for receiving objects to be colored and for conveying said objects in position below the stencils, means for causing said supporting-table to carry the objects thereon into engagement with the stencil, sprayers for each section, means for periodically causing movement of said sprayers to a position above said stencil, means for causing actuation of said stencil to allow application of coloring-matter to the objects for releasing said objects and for causing advancement thereof from one section to another.

4. In a pattern-printing machine, the combination with a main supporting-frame divided into a plurality of sections, a stencil for each section, a supporting-table disposed be-

low said stencils for supporting the objects to be colored, conveying mechanism for conveying objects to said supporting-table and in position below said stencils, means for causing vertical motion of said supporting-table to carry the objects into engagement with the stencils, sprayers for each section, means for moving said sprayers in position over the stencils, means for causing actuation of the sprayers only when the objects are held in engagement with the stencils by said table, and means for causing said carrier-frame to advance the printed objects from one section to another after application of coloring-matter thereto and to convey a fresh supply of uncolored objects to the stencils.

5. In a pattern-printing machine, the combination with a main supporting-frame, of a stencil secured thereto, a table for receiving an object to be colored, a carrier-frame for receiving an uncolored object and for conveying said object to said table in position below said stencil, means for causing movement of said table to carry the object thereon into firm engagement with the stencil, sprayers adapted to be moved into position above said stencil, means for causing actuation of said sprayers only when in position above said stencil and when said object is held in engagement with the stencil by said table, means after application of coloring-matter to the object for causing said table to remove the object from the stencil, and means for causing actuation of the carrier-frame to remove the colored object away from the stencil and to carry an uncolored object to the table below said stencil.

6. In a pattern-printing machine, the combination with a main supporting-frame, of a stencil secured thereto, sprayers adapted to be reciprocated longitudinally above said frame and periodically into position above the stencil, a table below said stencil for supporting an object to be colored, a carrier-frame adapted to be reciprocated transversely across said main supporting-frame and below said stencils for conveying objects to said table in position below said stencil, reciprocating means for said table for causing the object thereon to be carried into engagement with said stencil, means for causing actuation of the sprayers only when in position over said stencil, and means for causing said reciprocating carrier-frame to remove the colored object from the machine and to convey an uncolored object in position below the stencil.

7. In a printing-machine, the combination with a main supporting-frame divided into a plurality of sections, of a channel extending transversely across the top of said supporting-frame, a stencil for each section bridging over said channel, a supporting-table disposed within said channel for supporting the objects to be printed, conveying mechanism

traveling through said channel for conveying objects to be printed to the supporting-table, means for causing said table to carry the objects into engagement with the stencil, 5 sprayers adapted to be moved over said stencils, means for automatically causing actuation of said sprayers only when in position above the stencils, means for causing said table to remove the printed objects 10 from the stencils, and means for causing said conveying mechanism to carry away the objects from said stencils and to supply unprinted objects to said stencils.

8. In a printing-machine, the combination 15 with a main supporting-frame divided into a plurality of sections, of a channel extending transversely across the top of the supporting-frame, a stencil for each section bridging across said channel; a supporting-table in 20 said channel for receiving the objects to be printed, conveying mechanism adapted to reciprocate within said channel for carrying objects to be printed to said table below said stencils, means for causing said table to raise 25 the objects thereon into engagement with the stencils, printing apparatus adapted to be moved over said stencils when said objects are in engagement therewith, means for withdrawing said table and the objects 30 thereon after said objects are printed, means for causing said conveying mechanism to advance the printed objects from one section to the other after printing thereof, and means for causing said conveying mechanism to convey unprinted objects below said stencils. 35

9. In a printing-machine, the combination 40 with a main supporting-frame, of a channel extending transversely across the top thereof, a stencil bridging said channel, a table within 45 said channel for receiving objects to be printed, a carrier-frame adapted to be reciprocated in said channel for conveying objects to be printed to said table below said stencil, means for causing said table to carry 50 the object thereon into firm engagement with the stencil, sprayers, means for causing said sprayers to be moved over said stencil when the object is brought into engagement therewith, means for causing actuation of 55 said sprayers when in position over said stencils, means for withdrawing the printed object from said stencil, and means for causing said carrier-frame to carry said printed object away from the stencil and to substitute therefor an unprinted object.

10. In a coloring-machine, the combination 60 of a main supporting-frame having a channel extending across the top thereof, a stencil bridging said channel, a supporting-table within said channel for supporting objects to be colored, said table being normally removed from said stencil, a carrier-frame adapted to reciprocate within said channel for conveying objects to be printed to and 65 from said table, means for raising said table

to bring the objects thereon into engagement with said stencil, sprayers, means for causing said sprayers to be reciprocated across said stencil, means for causing actuation of said sprayers only when passing over said stencil, 70 and means for lowering said table after the object thereon has been colored, said carrier-frame causing said colored object to be removed from the machine and another uncolored object substituted therefor on said 75 table.

11. In a printing-machine, the combination with a main supporting-frame having a transverse channel extending across the top thereof, a stencil bridging said channel, a table arranged within said channel for supporting objects to be colored, cam mechanism for causing vertical reciprocation of said table for causing the object thereon to be brought into firm engagement with the stencil and to be removed therefrom after printing, a carrier-frame for said table, means for causing reciprocation of said carrier-frame to convey objects to be printed to and away from a position below said stencil, sprayers, 85 a supporting-frame for said sprayers, means for automatically causing said sprayers to be moved in position over the stencils when the object on the table is moved into engagement with the stencil, and means for allowing application of coloring-matter only when the object is in engagement with the stencil, said carrier-frame causing the printed object to be removed from the machine and another unprinted object to be substituted therefor 90 in position below said stencil. 95

12. In a printing-machine, the combination of a main supporting-frame having a channel extending transversely across the top thereof, a stencil bridging said channel, a table arranged within said channel for supporting the objects to be colored, a carrier-frame for carrying uncolored objects to said table, cam mechanism for causing said table to be raised when an object is in position 100 thereon under the stencil whereby said object is brought into engagement with the stencil, sprayers supported from a sprayer-frame, means for automatically moving said sprayers into position over said stencil when 105 said object is in engagement therewith, means for causing actuation of the said sprayers only when said object is in engagement with the stencil, and means for releasing said table to remove the printed object from said 110 stencil, further actuation of said carrier-frame causing the printed object to be carried from the machine and conveyed to a receptacle and an unprinted card supplied to the table in position below said stencil. 115

13. In a printing-machine, the combination with a main supporting-table divided into a plurality of sections, of a channel extending transversely over the top thereof, a stencil for each section bridging said channel, 120

a table within said channel below said stencil for supporting objects to be printed, a carrier-frame associated with said table, mechanism for causing reciprocation of said carrier-frame longitudinally along said table, means for causing said carrier to convey objects to said table below said stencils, cam mechanism for automatically causing said table to be raised to carry the objects thereon into firm engagement with the stencil, spray-
ers for each stencil, a sprayer-frame adapted to be automatically reciprocated across said channel to carry said sprayers into position above the stencils, means for causing actuation of said sprayers only when said objects are in engagement with the stencils, means for automatically lowering the table after the objects thereon have been printed, and means for causing said carrier-frame to advance the printed objects from one section to the other and to supply the first section with an uncolored object.

14. In a coloring-machine, the combination with a plurality of stencils, of supporting means for bringing objects into firm engagement with said stencils, means for conveying the objects to said supporting means, spray-
ers normally removed from said stencils, means for automatically carrying said spray-
ers in position over the stencils, means for automatically causing actuation of the sprayers only when said objects are in firm engagement with the stencils, and means for causing said conveyer mechanism to remove the colored objects from the stencils and to replace them with uncolored objects.

15. In a coloring-machine, the combination with a plurality of coloring fields, of sup-

porting means for the objects to be colored, conveyer means traveling through said fields 40 for conveying thereto the uncolored objects and for conveying therefrom the colored objects, sprayers for each field, means for automatically moving said sprayers within said fields, and means for automatically causing 45 actuation of said sprayers only when in proper position with respect to the objects to be colored.

16. In a coloring-machine, the combination with a plurality of coloring fields, of con- 50 veyer mechanism adapted to reciprocate through said fields for conveying uncolored objects thereto and for conveying colored objects therefrom, sprayers for each field, means for automatically causing said spray- 55 ers to be moved in position over the objects to be colored, and means for automatically causing actuation of said sprayers only when in proper position over the objects to be colored. 60

17. In a pattern-printing machine, a stencil secured to a supporting-frame, a table below the stencil, a feed-frame for delivering uncolored objects to the table in position below the stencil, means for intermittently raising the table for carrying an uncolored object against the stencil, and coloring means for directing coloring-matter to the stencil to color the object in engagement therewith.

In witness whereof I hereunto subscribed 70 my name this 10th day of February, A. D. 1905.

CHARLES LAURENCE BURDICK.
